UNITED STATES PATENT OFFICE.

BENJAMIN G. CALL AND RICHARD A. WAGSTAFF, OF GARFIELD, UTAH, ASSIGNEES TO AMERICAN SMELTING & REFINING COMPANY, A CORPORATION OF NEW JERSEY.

RABBLE-FURNACE CONSTRUCTION.

Application filed October 9, 1917, Serial No. 195,509. Renewed February 26, 1923.

To all whom it may concern:

Be it known that we, BENJAMIN G. CALL, a citizen of the United States, and resident of Garfield, county of Salt Lake, State of Utah, and RICHARD A. WAGSTAFF, a citizen of the United States, and resident of Garfield, county of Salt Lake, State of Utah, have invented certain new and useful Improvements in Rabble-Furnace Constructions, of which the following is a specification.

The invention relates in general to an ore roasting furnace and particularly relates to improvements in the shaft, in the rabble arms and in the rabbles used in radial multiple deck ore roasting furnaces.

One of the objects of the invention is to provide an improved form of air cooled type of construction of the class described, which will effectively cool the apparatus and at the same time minimize the size of structural parts and the amount of material necessary to effect this improved cooling of the parts subjected to the heat from the furnace.

Another object of the invention is to provide a construction of rabbles and their correlated parts so designed that burnt out or damaged parts may be readily replaced without the necessity of demounting the entire organization and without materially effecting the position of the undamaged rabbles on any one rabble arm.

Still another object of the invention is to provide a simply constructed means for supplying air to the hearth of the furnace and an object incidental to the last decideratum is to provide a simple form of means for controlling this air supply.

Various other objects and advantages of the invention will be in part obvious from an inspection of the accompanying drawings and in part will be more fully set forth in the following particular description of one form of mechanism embodying my invention, and the invention also consists in certain new and novel features of construction and combination of parts hereinafter set forth and claimed.

In the drawings:

Figure 1 is a vertical sectional view taken axially through a multiple hearth roaster showing a preferred embodiment of our invention installed therein and shown in side elevation;

Figure 2 is a vertical sectional view taken

axially through the central shaft and one of the rabble arms;

Figure 3 is a transverse sectional view taken on the line 3-3 of Figure 2;

Figure 4 is a similar view taken on the line 4-4 of Figure 2;

Figure 5 is a transverse sectional view through one of the rabble arms and taken on the line 5-5 of Figure 2;

Figure 6 is a fragmentary view of a portion of a rabble arm and attached rabbles looking upwardly from underneath the arm;

Figures 7 and 8 are respectively a view in side elevation and a view in plan showing details of the clamp for holding the rabble to the rabble arm; and

Figures 9, 10 and 11 are respectively a plan view, a view in side elevation and a view in end elevation of the rabble.

In the drawings there is shown a conventional form of multiple hearth furnace 10, including a bottom hearth 11, a top dome drying hearth 12, and certain intermediate hearths 13. Centrally positioned to extend through the several hearths is an upstanding shaft 14 formed of a plurality of sections, one section for each of the intermediate hearths and a section for the bottom hearth. These sections include radial arms 14', a pair of diametrically disposed arms for each of the spaces between adjacent superposed hearths and with the arms in one hearth disposed at 90° from the arms in the hearth spaces just above and below the same.

As these sections are similar in construction it will be understood that the detail description of any one section will be sufficient for any other similar section.

Referring particularly to Figure 2 it will be noted that each section is formed of a tubular member 15 provided at opposite ends with outstanding flanges 16' by means of which it may be attached to the similar section above and below the section described. The member 15 is provided with a central partition 16 designed, when the several sections are assembled, to be positioned in line with and form a continuation of the similar partitions in the next adjacent sections thereby to form a two-compartment air passageway through the column. One of the passageways 17 is opened at the bottom through the air inlet or outlet 18 and similarly the other passageway 20 is opened

at the top through the inlet or outlet 21. Either of these outlets may be suitably connected to an air current producing means or arranged to discharge either the hot or cold air as may be desired. Each of the sections is provided centrally thereof with a circular wind box 22 inclosing the cylindrical member 15 and spaced therefrom to form a double decked wind passageway 23. Diametrically opposite sides of the wind box are formed into outwardly extending bells 24, the outer end of each of which is provided with a flange 25 constituting a means for fastening the rabble arms 14 thereto.

Each of the rabble arms is provided with a horizontally disposed partition 26, which has its inner end affixed to the tubular member 15 and has its outer end spaced a short distance from the outer end 27 of the rabble arm thereby to form a passageway 29 connecting the lower side 30 and the upper side 31 of the rabble arm. This lower side 30 of the rabble is connected to the lower portion of the air chamber 23 which lower side is in fluid communication with the passageway 20 through an opening 32 in the side of the member 15. Similarly the upper side 31 of the rabble arm is connected through the upper side of the compartment 23 and is in fluid communication with the passageway 17 through an opening 33 in the side of the tubular member 15, all as more particularly shown in Figure 2.

By this construction it will be obvious that air may be introduced either at the top or bottom of the shaft and passed successively through each side of the rabble arms, cooling the same during its passage. The finally heated air may be discharged onto the hearth or piped into any of the metallurgical devices which can utilize heated air to advantage.

For the purpose of supplying hot air to the hearths in the device disclosed, the wind boxes are provided with port holes 34 positioned in the side thereof, which holes are normally closed by means of cover plates 35.

The rabble arms carry a plurality of rabbles 40 as is usual in devices of this character. For the purpose of supporting the rabbles demountably in position, the lower side of the arm is flattened to form laterally extending ledges 41 in a bottom plate 42. A plurality of rabble guiding members or clamps 43 are slidably mounted on the ledges 41 so that the clamps can be slid longitudinally back and forth along the length of the rabble arms. Each side of the clamps is provided with a rabble supporting ledge 44, with the ledge on one of the clamps coacting with the corresponding ledge on the adjacent clamp to form a supporting means for engaging under and supporting the T-head 45 of the rabbles 40 as shown in Figure 6.

Each of the rabbles is provided with an

air conducting passageway 46 which opens through the head 45, extends within a short distance from the lower end of the rabble and is then turned 90° to exit through the port 47 at the rear side and near the edge of the blade portion 48 of the rabble. The plate 42 is provided with a plurality of apertures 49 spaced apart longitudinally thereof and designed to place the hearth spaces in communication with the interior of each of the rabble arms when the rabbles are set in their fixed position.

Under some conditions of roasting it is found desirable to provide a means for controlling the flow through the passageways 46 and for this purpose each of the rabble arms is provided with a damper plate 50 slidably mounted on the top of the plate 42. The damper plate is guided between guiding walls 51 formed in the interior of the rabble arms and is provided with a plurality of openings 52 extending therethrough and spaced apart to correspond to and be placed in alignment with the opening 49 at the bottom of the rabble arm. For the purpose of providing access to the damper plate, the outer, lower end of the rabble arm is provided with an opening 53 through which an instrument may be inserted to engage and shift the damper plate and thus regulate the extent of opening through the apertures 49.

In operation it will be understood that the central column is revolved, carrying with it the rabble arms and that the material to be roasted is fed into the furnace and is moved from one hearth to another by means forming no particular part of this invention.

Air is passed by its natural draft or by providing artificial draft creating means at either or both ends of the column. This cooling air is passed up one of the passageways 17 or 20, the other passageway constituting the discharge for the air heated in its passage through the rabble arms. While a large proportion of the air will pass from one to the other side of the partition 26 through the passageway 29, it is obvious that some air will be discharged through the rabbles onto the hearths, and the amount of this air is regulated at each arm simply by shifting the damper plate contained in the arm.

If at any time one of the rabbles should become burned, or otherwise damaged, the rabbles and corresponding guide plates to the outside of the damaged rabble are shifted outwardly on the rabble arms and the damaged part permitted to drop out of position onto the hearth. The other rabbles may be shoved back into position or a new rabble may be inserted in place of the damaged rabble.

While we have shown and described, and have pointed out in the annexed claims, certain novel features of our invention, it will

be understood that various omissions, substitutions and changes in the form and details of the device illustrated and in its operation may be made by those skilled in the art without departing from the spirit of the invention.

Having thus described our invention, we claim:

1. In a device of the class described, a rabble construction including a pair of superimposed sections, each section including an upstanding tubular hub a wind box surrounding the hub and a radially disposed arm leading outwardly from each wind box, each tubular hub provided with a central partition designed to be disposed in line with and forming a continuation of the partition in the next adjacent section thereby to form a double passageway through the pair of sections and each passageway opening into the wind box.

2. In a device of the class described, a rabble construction including a pair of superimposed sections, each section including an upstanding tubular hub and a radially disposed arm, each tubular hub provided with a diametrically extending central partition designed to be disposed in line with and forming a continuation of the partition in the next adjacent section thereby to form the hub into two passageways of approximately equal cross-section through the pair of sections, said arm being hollow and having two air ports one open to one of said passageways and the other open to the other passageway in the hub.

3. In a device of the class described, a rabble construction including a pair of superimposed sections, each section including an upstanding tubular hub and a pair of hollow radially disposed arms, each tubular hub provided with a central diametrically extending partition designed to be disposed in line with and form a continuation of the partition in the next adjacent section thereby to form a double passageway through the pair of sections, one of said arms being open to one of the passageways and the other arm of each section being open to the other passageway and said arms being each offset from the next adjacent arms when considered circumferentially.

4. A revolvable column for multiple hearth roasting furnaces comprising a plurality of sections demountably fastened together, one of said sections including a tubular member provided with a centrally disposed partition to form two passageways therein, an air drum surrounding said tubular member and spaced therefrom to form a wind passageway, a rabble arm extending radially from said air drum, a horizontally disposed partition extending from the tubular member to form an upper and a

lower wind way in said arm, one of said wind ways in the arm being open to one of the passageways in the tubular member and the other wind way in the arm being open to the other passageway in the tubular member.

5. In a device of the class described, a rabble arm provided with an air passageway for conducting air through the arm, said arm provided with a small air outlet leading from said passageway and a rabble receiving air from said outlet.

6. In a device of the class described, a rabble arm provided with air passageways for conducting air through the arm, said arm provided with a small air outlet opening through the underside thereof and leading from one of said passageways and a conduit for conducting the air from said outlet into the space below the arm.

7. In a device of the class described, a rabble arm provided with an air passageway for conducting air through the arm, said arm provided with a small air outlet leading from said passageway and a valve for controlling the flow of air through said outlet.

8. In a device of the class described, a rabble arm provided with an air passageway for conducting air through the arm, said arm provided with a line of air outlets opening from said passageway, and a valve plate slidably mounted in said arm to control the flow of air through said outlets.

9. In a device of the class described, a hollow rabble arm provided with an air passageway therein for directing a current of air through the arm, and a rabble mounted on said arm said rabble provided with an air passageway therein open to the passageway in the arm.

10. In a device of the class described, a hollow rabble arm provided with an air passageway therein for directing a current of air through the arm and a plurality of hollow rabbles demountably positioned on said arm, said rabbles being open to the passageway in the arm whereby air is passed through the arm and through the rabbles.

11. As an article of manufacture, a rabble provided with means for mounting the same on a rabble arm, said rabble provided with a passageway therein for conducting air therethrough.

12. In a device of the class described, the combination of a rabble arm provided with an air outlet, a rabble guide mounted on said arm and a rabble positioned in place on the arm by said guide and provided with an air passageway adapted to be located by the guides in position to communicate with the air outlet from the rabble arm.

13. In a device of the class described, an attachment to a rabble arm, including a pair of rabble guides adapted to be mounted

side by side on a rabble arm, and each guide provided with supporting means coactively adapted to support a rabble therebetween, and a rabble supported in position by said supporting means, said rabble provided with an air conducting passageway in spaced relation to the supporting guides.

14. In a device of the class described, the combination of a shaft constituting an air tube, said shaft formed of a plurality of sections each provided with a partition disposed in alignment with the adjacent section to form a two-compartment air tube, certain of said sections being provided with wind boxes surrounding the sections, and a hollow arm extending outwardly from the wind box and in fluid communication therewith.

15. In a device of the class described, the

combination of a shaft constituting an air tube, said shaft formed of a plurality of sections each provided with a partition disposed in alignment with the adjacent sections to form a two-compartment air tube, certain of said sections being provided with wind boxes surrounding the sections, a hollow arm extending outwardly from the wind box and a horizontally disposed partition extending from the air tube outwardly through the hollow arm, the lower side of the arm being in fluid communication with one of the compartments and the upper side being in fluid communication with the other compartment.

This specification signed this sixth day of September, 1917.

BENJAMIN G. CALL.
RICHARD A. WAGSTAFF.
